UNITED STATES PATENT OFFICE.

KOHATH ANTHONY, OF WILMERDING, PENNSYLVANIA, ASSIGNOR OF ONE-HALF TO A. L. TREVASKIS, OF TURTLE CREEK, PENNSYLVANIA.

FRESH-AIR CONVEYER.

No. 870,407.

Specification of Letters Patent.

Patented Nov. 5, 1907.

Application filed May 17, 1907. Serial No. 374,250.

To all whom it may concern:

Be it known that I, KOHATH ANTHONY, a citizen of the United States of America, residing at Wilmerding, in the county of Allegheny and State of Pennsylvania, have invented certain new and useful Improvements in Fresh-Air Conveyers, of which the following is a specification, reference being had therein to the accompanying drawing.

This invention relates to fresh air conveyers particularly designed for invalids.

The invention has for its object to provide positive and reliable means for conveying fresh air from the exterior of a building to an invalid within the building, whereby the invalid or patient will not inhale the air of the compartment in which they are located.

My invention aims to provide a novel air conveyer for invalids that can be adjusted for conveying air, a short or long distance, depending upon the location of the invalid with respect to a window. The conveyer is constructed whereby it can be easily and quickly placed in the frame of a window, to convey fresh air to an invalid, without exposing other occupants of the compartment or the invalid's body to fresh air.

The detail construction entering into my invention will be hereinafter more fully described and then specifically pointed out in the appended claims.

Referring to the drawing forming part of this specification, like numerals of reference designate corresponding parts throughout the several views, in which— Figure 1 is a perspective view of the air conveyer illustrating the manner in which the same is used. Fig. 2 is a detail sectional view of the mask portion of the conveyer. Fig. 3 is an elevation of one of the folding plates used in connection with the conveyer. Fig. 4 is an enlarged cross sectional view of the same.

The fresh air conveyer consists of a flexible mask 1 adapted to be placed over the face of an invalid, the mask being preferably made of fine meshing wires. The lower portion of the mask is connected to a flexible hood 2 carrying a metallic band 3 adapted to be detachably connected to a band 4, which supports the inner ends of flexible conduits or tubes 5 and 6. In the conduits or tubes 5 and 6 are arranged coiled springs 7 for preventing the conduits or tubes from collapsing, thus insuring a passage through the conduits or tubes whether expanded or contracted.

The outer ends of the conduits or tubes 5 and 6 are connected to folding boards 8 and 9 respectively, said

boards being provided with openings 10, covered with screens 11 whereby solid matter cannot enter the conduits or tubes 5 and 6. The board 8 is placed in a window frame 12 between the top of said frame and the upper rail of the top sash 14, while the board 9 is placed between the sill of the frame 12 and the bottom rail of the lower sash 15.

When the invalid or patient is located a considerable distance from the window of a compartment, I suspend the ring or band 4 upon the end of a cable 16 from the ceiling of a compartment or the bed frame, whereby the mask can be retained upon the invalid's face, thus permitting of an invalid's head moving without necessarily disarranging the mask 1. Fresh air will be conveyed to the invalid through the conduit or tube 6, and the air exhaled by the invalid will pass upwardly and out of the window through the conduit or tube 7.

It is thought that the various uses to which my improved fresh air conveyer can be put will be apparent to hospital attendants and persons skilled in attending invalids.

I do not care to confine myself to the material from which the hood and conduits are made, or to the manner of supporting the mask end of the conveyer.

What I claim and desire to secure by Letters Patent, is:—

1. A fresh air conveyer consisting of a mask, a hood connecting therewith, detachable bands connecting with said hood, flexible conduits connecting with one of said bands, coiled springs arranged in said conduits, a folding board connecting with each conduit and having a screened opening formed therein for admitting air to said conduit, substantially as described.

2. The combination with a window frame, and the sashes thereof, folding boards adapted to fit in said frames beneath the lower sash and above the top sash of said frame, said boards having openings formed therein, flexible conduits communicating with the openings of said boards, a hood connecting with said conduit, and a mask carried by said hood.

3. The combination with a window frame, of boards adapted to fit at the bottom and top of said frame, said boards having openings formed therein, flexible conduits connecting with said boards, a hood communicating with said conduits, and a mask carried by said hood.

In testimony whereof I affix my signature in the presence of two witnesses.

KOHATH ANTHONY.
